UNITED STATES PATENT OFFICE

CARLOS A. SMITH, SR., OF BELLAIRE, OHIO

RUG-CLEANSING MECHANISM

Application filed August 29, 1928. Serial No. 302,731.

This invention relates broadly to carpet cleansing mechanisms, and more specifically to an apparatus for removing cleansing fluid from carpets and rugs which have been scrubbed.

The primary object of the invention is to provide a scrubbing machine for floor coverings having embodied therein adjacent to the scrubbing rolls mechanism where-
10 by the nap of the covering is raised and, at the same time, much of the cleansing water, chemicals, or other material em-
ployed, is removed together with the for-
eign matter collected in the covering.

15 A still further object is to provide, in a rug scrubbing apparatus, means whereby the moisture is removed from rugs, leaving the latter in much the same condition as if subjected to the action of wringing rolls,
20 except that the nap of the rugs is raised, or elevated, instead of being flattened upon the bodies of the rugs.

25 And another object is to structurally improve and increase the efficiency of the scrubbing apparatus disclosed in my prior Patent No. 1,668,255, dated May 1, 1928.

In describing the invention in detail, reference is herein had to the accompanying drawings, in which—

30 Figure 1 is a top plan view of a portion of a rug scrubbing apparatus, showing my invention applied thereto;

Figure 2 is a side elevation of the same;

35 Figure 3 is an enlarged sectional elevation, the section being taken on line 3—3, Fig. 1;

Figure 4 is an enlarged view, partially in top plan and partially in section, of one of the fluid removal units;

40 Figure 5 is a sectional elevation, the section being taken on line 5—5, Fig. 1; and—

45 Figure 6 is a sectional elevation of a structural detail, the section being taken on line 6—6, Fig. 1.

Referring to said drawings, 1 designates the side members of the frame of a scrubbing apparatus of the character disclosed in my Patent No. 1,668,255, hereinbefore referred to, said members being carried on

cog wheels 2 arranged for travel along trackways 3 embodying gear rack teeth 4.

Mounted on the frame 1 in a position located rearwardly of the scrubbing rolls, or cylindrical brushes 5, is a vertically elevat-
55 able frame comprising side members 6. Interposed between said side members adjacent to one end of the latter are transversely disposed bars or rods 7 upon which are slidably supported upright hanger-like supports 8 having attached thereto, or formed integrally therewith, a fluid removal unit des-
ignated generally by the reference number 9. Said unit comprises a cast metal housing 60 which has formed therein a plurality of 65 parallel transversely disposed bores, cham-
bers, or compartments 10 of substantially cylindrical form, said compartments being open in their under sides, as shown in Fig.
3, and having closed ends 11. Journalled 70 in the ends 11 of said housing are the ends of a plurality of propellers 12 of spiral, or screw, form, one such propeller being more or less closely fitted for rotation within each of the compartments 10 and having the 75 under side of its spiral blade projecting outward through the open under side of the compartment for engaging a carpet or rug which is being cleansed.

Said propellers protrude such a distance 80 that, in the completely lowered position of the unit, the blades thereof penetrate the nap to, or substantially to, the woven body of the rug.

Water or other cleansing or rinsing fluid 85 is supplied through the top of the housing 9 to the various compartments 10 at points adjacent to the inner ends of the latter from a distributor pipe 13 to which it is conducted in any suitable manner, as by a flexible hose 90 (not shown) attached to a nipple 14. This rinsing fluid, together with the scrubbing fluid employed in connection with the scrub-
bing rolls 5 and which remains following 95 passage of said scrubbing rolls, is propelled by the propellers in an outward direction, said propellers serving to squeeze and force from the rug surface a very large percent-
age of the fluid and collected dirt and to 100 convey the same from the rug. This fluid is

discharged outwardly through pipes 15 to a therewith communicating discharge pipe 16, from the outlet end or nipple 17 of which may lead a flexible drain tube (not shown).

5 While the unit 9 hereinbefore described may be made of any appropriate length, such length being measured transversely with respect to the length of the scrubbing machine, it is preferred that its length be 10 materially less than the width of the machine, or approximately one-half said width, in which case the unit is complemented by 15 a second unit 18 which is preferably located in a position rearward of the unit 9 and laterally with respect to the latter. Said 20 unit 18 is stationarily mounted, being carried in underslung relation to transversely disposed beams 19 which have their ends rigidly mounted upon the side members 6 of the elevatable frame.

25 The structure of the unit 18 corresponds in the main with that of the unit 9, embodying a housing with compartments in which operate spiral propellers. Water or rinsing fluid is supplied to said compartments through a distributor pipe 13^a and is discharged to and through a pipe 16^a.

As hereinbefore stated, the unit 18 is stationarily mounted on the beams 19 fixed to 30 the frame members 6, and the unit 9 is slidably carried by rods 7 having their ends mounted on said frame members. An adjusting screw or worm shaft 20 is journaled adjacent to its opposite ends in said frame members and is so engaged with the supports 8 that rotation thereof, effected 35 through the agency of a hand wheel 21 carried on an end thereof, causes said supports and the thereby carried unit 9 to shift laterally, the purpose being to adjust the unit 40 to the extent required for accommodating the fluid removal units to varying widths of rugs.

The propellers of the stationary unit 18 45 carry on their inner ends sprocket wheels 22 driven by suitably arranged sprocket chains 23 and 24, the latter being driven from a sprocket wheel 25 fixed on a shaft 27 journaled on the frame members 6. Fixed on the inner side member 8 is a sleeve 50 26 which is slidable along the shaft 27 in shifting movements of the unit 9, and carried by said sleeve is a sprocket wheel connected by a sprocket chain 45 to a similar 55 sprocket wheel carried on the end of one of the propellers 12, which latter drives the remaining propellers 12 through the intermediacy of a sprocket chain 46 operatively associated with sprocket wheels carried by 60 the ends of said propellers. Said shaft 27 carries on its outer end a gear wheel 28.

In elevating and lowering movements of the structure, wherein the latter is moved, respectively, out of and into operative relation 65 to a rug to be cleansed, said gear wheel

28 is moved out of and into mesh with a gear wheel 29 carried by a shaft 30 which is connected, as by a drive belt 31 to a motor driven shaft, as 32, of the machine. Said sleeve 26 is non-rotatable with respect to 70 the shaft, being engaged with a longitudinal channel 33 provided in the latter. Thus, as is apparent, shifting of the unit 9 is effected by rotation of the worm shaft 20, said unit traveling along the supporting rods 7 and 75 without changing the driving relations of the various sprocket wheels and chains.

A transverse rod 39 has fixed on each of its opposite ends a cam or eccentric 40 which rests on the adjacent side member 1 of the 80 machine, and it carries on one end thereof a hand lever 44 whereby rotary movements may be imparted thereto for effecting elevating and lowering movements of the frame 85 which includes the end members 6. Each of said cams occupies underlying relation to the middle portion of the adjacent member 6 so that, in one position thereof, said members are lowered to the extent that the units 9 and 18 occupy their operative position, and in another position of said cams, as shown in dotted lines in Fig. 5, said members are elevated for withdrawing said units to inoperative positions.

Trunnions 41 carried by each of the frame 95 members 6 are vertically movable in guide slots 42 provided therefor in brackets 43 which are mounted on the side members 1 of the scrubbing machine.

What is claimed is—

1. In a machine of the character described, a base, a fluid removal device comprising an elevatable support slidably mounted on said base, a plurality of spaced independent housings carried by said support, one of said 105 housings being shiftable laterally of the machine, each of said housings being provided with a plurality of cylindrical compartments having their under sides open throughout the lengths thereof, a screw propeller journaled for rotation in each of said compartments and having the blade thereof protruding through the under-side opening for engaging the surface of an underlying rug, means for rotating said propellers, and means for conducting from said chambers fluid collected by said propellers.

2. A machine of the character described comprising a base, a vertically movable frame on said base, a housing carried by said frame formed to provide a cylindrical chamber having an open bottom, a screw propeller journalled in said chamber and having a portion thereof extending through the open bottom of the chamber for engaging the nap of a rug, and means for rotating said propeller, thereby to remove collected fluid from the rug and to raise the nap.

3. A machine of the character described, comprising a base, a movable frame on said

base, a pair of spaced independent housings carried by said frame each being formed to provide a cylindrical chamber having an open bottom, a screw propeller journalled in each of said chambers and having a portion thereof extending through the open bottoms of the chambers for engaging the nap of a rug, means for rotating said propellers thereby to remove collected fluid from the rug and to raise the nap, and means for raising the frame and housings out of engagement with the rug.

4. A machine of the character described, comprising a base, a vertically movable frame on said base, a housing carried by said frame formed to provide a cylindrical chamber having an open bottom, a second housing carried by said frame formed to provide a cylindrical chamber having an open bottom, a screw propeller in each of said chambers having a portion extending through said open bottoms for engaging the nap of a rug, means for shifting one of said housings laterally of the frame relative to the other of said housings, and means for rotating said propellers.

5. A machine of the character described, comprising a base, a horizontally and vertically movable frame on said base, a housing secured to said frame formed to provide a chamber having an open bottom, a rotatable cleaning member in said chamber having a portion extending through the open bottom for engaging a rug, a second housing slidably mounted upon said frame and formed to provide a chamber having an open bottom, a rotatable cleaning member in said housing having a portion extending through the open bottom for engaging a rug, means for driving said cleaning members, means for elevating the frame and housings and means for shifting the last named housing transversely of said frame and relative to the other of said housings whereby rugs of varying widths may be cleaned.

In testimony whereof, I affix my signature.
